KNITTING MACHINE

George C. Szabo, Knoxville, Tenn., assignor to
 Holston Manufacturing Company, Knoxville,
 Tenn., a corporation of Tennessee

Application June 21, 1934, Serial No. 731,632

1 Claim. (Cl. 66—42)

This invention relates to knitting machines, and it has reference more particularly to circular stocking knitting machines having reverse plating sinkers and mechanism to selectively control the sinkers for the production of ornamental effects in the fabric.

My invention is directed in the main toward securing more diversified ornamentation in the stockings knit on machines of the type referred to than possible by reverse plating alone, and at the same time obtaining an increased output from the machines. These desiderata I realize in practice as hereinafter more fully explained, through provision of a supplemental feed to serve to the needles of the machine, an auxiliary yarn contrasting with the two yarns ordinarily used in the plating, and of a supplemental stitch cam for actuating the needles to knit the auxiliary yarn during each rotation of the needle cylinder. As a result, the rate of production of the ornamented portions of the stockings is doubled with formation of horizontal stripe effects by contrasting alternate courses of the knitting to embellish the reverse plated ornamentation.

Another object of my invention is to provide automatic means for withdrawing the auxiliary yarn feed and the supplemental stitch cam during the knitting of the heel and toe pockets of the stockings.

Other objects and attendant advantages will be manifest from the detailed description following of the attached drawings, wherein Fig. I is a side elevation of a circular reverse plating knitting machine conveniently embodying the present improvements.

Fig. II is a fragmentary plan view of the machine.

Fig. III is a fragmentary plan sectional view on a larger scale taken as indicated by the arrows III—III in Fig. I.

Fig. IV is a horizontal sectional view taken on a lower plane as indicated by the arrows IV—IV in Fig. I.

Fig. V is a fragmentary detail sectional view taken as indicated by the arrows V—V in Fig. III.

Fig. VI is a diagrammatic view showing the development of the knitting cams, the needles and the yarn feeds of the machine; and

Fig. VII is a view showing ornamented fabric such as may be produced through my invention.

Generally speaking, the circular knitting machine chosen for the purposes of illustration herein is of well known construction in that it comprises a needle cylinder 10 which is supported for

rotation in a bed plate 11 at the top of the framework 12 of the machine. As usual, the needle cylinder 10 is rotated and oscillated incident to knitting of stockings by mechanism including a bevel gear 13 which, see Fig. I, is mounted on a horizontal shaft 14. Also as usual, the machine is provided with five yarn fingers of which the ones numbered 15, 16 and 17 only are used in this instance to respectively feed contrastingly colored plating yarns P, P', and the heel and toe yarn H, said fingers being independently pivoted on an axis pin 18 in upstanding lugs 19 of the latch guard ring 20, and controlled, through the medium of thrust rods 21, 22 and 23 (Fig. IV) from the main cam drum 15 24 of the machine.

The knitting needles 25 in the cylinder 10 are actuated by the conventional stitch cams which are shown at 26 and 27 in Fig. VI, and which are disposed at opposite sides of a top center 20 cam 28 and a bottom guard cam 29, this cam group being located as ordinarily, directly below the yarn feed fingers 15—17. The needle actuating mechanism also includes a pair of lifting pickers 30 and 31, and a drop picker 32, which 25 cooperate in the well known manner incident to the fashioning of the heel and toe pockets of the stockings by oscillatory knitting.

The sliding sinkers indicated at 33 are of a conventional type adapted for reverse plating, 30 said sinkers being lodged, as usual, in the radial guide grooves of a dial 34 on the needle cylinder 10, and actuated by the cam groove 35 of the sinker cap ring 36, see Figs. III and V. As shown in Fig. V, the sinkers 33 have special butts 33a 35 at different levels for the purposes of selective actuation, by leaf spring cams 37 and 38 which are secured to the top of the sinker cap ring 36, and which are respectively operated by thrust rods 39 and 40, and 41, 42, 43 with overhanging 40 noses arranged at opposite sides of the group of thrust rods 21—23 associated with the yarn feed fingers 15—17. The thrust rods 39—43, like the thrust rods 21—23 for actuating the yarn feed fingers 15—17, are ordinarily controlled from the 45 main cam drum 24 of the machine, but during reverse plating, for example, of the leg portion and instep portions of the stockings, said rods are actuated from a supplemental pattern drum 45 through the instrumentality of individually 50 associated lifting bell crank levers 46 whereof the pendant arms are fitted with cam ends to cooperate with suitably-allocated circumferential rises on said supplemental cam drum. As shown, the bell crank levers 46 are mounted for 55

independent movement on a common fulcrum rod 47 projecting laterally from a bracket 48 attached to the machine frame 12, said bracket also supporting the axis pin 49 upon which the drum 45 is free to rotate. Intermittent movement is imparted to the drum 45, in clockwise direction as considered in Fig. I, through picking of a ratchet wheel 50 connected thereto, by a hook pawl 51. As shown in Fig. I, this hook pawl 51 is pivotally connected at 52 to a vertical arm 53 fulcrumed on a fixed stud 54 at the front of the machine. At its upper end the arm 53 carries a roller 55 which runs in contact with the edge of a cam 56 on the shaft 14 previously referred to. Furthermore as usual, the machine is provided with a measuring chain 57 trained about a sprocket wheel 58 which is free on a shaft 59 suitably supported by the machine frame 12, and which is intermittently progressed in the known manner by suitable means coordinated with the drive mechanism of the machine.

In adapting a knitting machine such as above briefly described to the purposes of my invention, I provide a longitudinally adjustable auxiliary yarn finger 60 which I pivot for up and down movement on the axis pin 18 that serves the usual yarn feed fingers 15-17, see Figs. I and II, said auxiliary yarn finger reaching to a point substantially 180° from the usual yarn fingers, and terminating in an eye 61 for feeding to the needles, a third yarn A contrasting in color with the plating yarns P, P'. During the knitting of reverse plated ornamented leg and instep portions of the stockings, the auxiliary yarn feed finger 60 occupies the active position illustrated in full lines in Figs. I and VI. The auxiliary yarn finger 60 is controlled by a vertical thrust rod 62 whereof the lower end is connected at 63 to the thrust rod 22 which controls the heel and toe yarn finger 16 and which is actuated by the usual circumferentially spaced peripheral lugs 64 on the main cam drum 24 of the machine. The upper end of the thrust rod 62, it will be noted, is bent laterally to engage a set screw 65 adjustable in the rearward projection or tail of the auxiliary yarn finger 60. A tension spring 66 serves to yieldingly maintain the set screw 65 in contact with the laterally bent end of the thrust rod 62, and in turn, to keep the lower end of said rod engaged with the thrust rod 22 as clearly shown in Fig. I. When the thrust rod 22 rides off the special cam lugs 64 on the cam drum 24 to permit the heel and toe yarn feed finger 16 to swing down to active position, the spring 66 concurrently operates to raise the auxiliary yarn feed finger 60 to the dot-and-dash line inoperative position shown in Fig. I, in which position it is maintained during the knitting of the heel and toe pockets of the stockings with the yarn H.

In order that fabric loops may be formed from the yarn A served by the auxiliary finger 60, I have provided an auxiliary stitch cam 68, see Figs. I-IV and VI which is carried by a horizontal arm 69 fulcrumed at 70 to the bed plate 11 of the machine. During the knitting of the leg and instep portions of the stockings the auxiliary stitch cam 68 is held in the active position shown in Fig. IV in opposition to a tension spring 71 by means of a cam finger 72 which is fulcrumed intermediate its ends at 73 to the bed plate 11 of the machine. As shown, the free end of the cam finger 72 engages an upstanding stud 74 carried by the arm 69, while its other end is coupled by means of a link rod 75 with a vertical lever 76 fulcrumed at 77 to a fixed pin projecting laterally

from the machine frame 12. Beyond its pivot, the arm 16 is formed with a finger 18 adapted to cooperate with special circumferentially-spaced peripheral cam lugs 79 and 80 on the main cam drum 24 of the machine, so that, during the knitting of the heel and toe pockets of the stockings, the auxiliary stitch cam 68 is retracted to idle position concurrently with the withdrawal of the auxiliary yarn finger 60. I have also provided, as shown in Figs. III and V, an auxiliary cam 81 for retracting the sinkers 33 at the region where the needles 25 draw fabric loops from the auxiliary yarn A under the influence of the auxiliary stitch cam 68.

The operation of the machine is as follows: 15
Let it be assumed that the machine is knitting the leg portion of the stocking with the usual feed fingers 15 and 17 in active position as shown in Fig. VI and serving the two differently colored yarns P, P' in plating relation to the needles 25, 20 and that the auxiliary feed finger 61 is at the same time serving the contrastingly-colored yarn A. As the knitting proceeds, the spring cam fingers 37, 38 are variously manipulated by the thrust rods 39, 40 and 41—43 under the governance of the supplemental pattern drum 45 so that the sinkers 33, prearranged in the sinker ring 36 in accordance with their different butt heights, are actuated selectively to produce a pattern design by reverse plating. During each rotation of the machine, as the sinkers 33 approach the auxiliary feed 61 they are retracted by the special cam 81, (Fig. III), during the time that the needles draw loops from the auxiliary yarn A at said feed, returning however to their normal position in readiness to be actuated for the purpose of reverse knitting as they again approach the plating yarn feeds 15 and 17. As a consequence of the described arrangement it is possible to produce pattern effects such as exemplified in Fig. VII of the drawings wherein the three yarns are respectively indicated by the same reference numbers heretofore employed. As shown, the fabric is characterized by alternation of single loop courses 82 formed from the auxiliary yarn A, with reverse plated double loop courses 83 formed by the plating yarns P, P'. 30 35 40 45

From the foregoing it will be evident that, through my invention it is possible to obtain a variety of pattern effects over those determinable by reverse plating alone with differently colored yarns, and moreover to secure an increased output from the knitting machines by virtue of successively feeding two yarns and forming two fabric courses from them during each rotation of the machines. 50 55

Having thus described my invention, I claim:—

In a circular stocking knitting machine, a pair of pivoted feed fingers for serving two differently-colored yarns in plating relation to the needles; an associated normally-inoperative pivoted finger for serving a heel and toe yarn to the needles; thrust rods for controlling the aforesaid feed fingers; a rotary drum for actuating the thrust rods; means to cooperate with the needles to produce ornamental effects in the fabric by prescribed reversal of the plating yarns; means for actuating the needles to knit the plating yarns; an auxiliary feed for serving a third contrasting yarn to the needles during each rotation of the machine; a separate auxiliary stitch cam for actuating the needles to knit the auxiliary yarn, with formation from the latter, of plain single loop fabric courses in alternation with the double loop fabric courses produced with the plating 60 65 70 75

yarns; connections from the auxiliary yarn feed aforesaid to the actuating thrust rod for the heel and toe yarn feed; connections from the auxiliary stitch cam with the cam drum aforesaid; and 5 peripheral cam lugs on said drum respectively to effect the withdrawal of the auxiliary stitch cam, and for operating the thrust bar controlling

the heel and toe yarn feed to concurrently effect withdrawal of the auxiliary yarn feed from action and placement of the heel and toe yarn feed into action for the knitting of the heel and toe pockets.

GEORGE C. SZABO.
